UNITED STATES PATENT OFFICE.

WILLIAM R. HUTTINGER, OF PHILADELPHIA, PENNSYLVANIA.

HIGH-VOLTAGE SWITCH.

Application filed January 29, 1924. Serial No. 689,256

My invention relates to electric switches, having particular relation to high-tension electric switches.

One object of my invention is to provide 5 an electric switch which is characterized by its ruggedness of construction, yet relatively light weight; by its particular applicability to high-tension lines having exceedingly high voltages, say 155,000 volts and over; and by 10 its adaptability to motor operation.

Another object of my invention is to provide a high-tension switch which is unaffected by such accumulations of ice, snow, or sleet as would render inoperative the ordinary type 15 of high-tension switches of the prior art.

A further object of my invention is to provide a disconnecting switch, comprising a pair of rigidly positioned insulators providing supports for stationary and movable 20 switch elements, respectively, an actuating insulator, and means for so operatively associating the actuating insulator and the movable switch element that the torsional strain in the actuating insulator is reduced to a 25 minimum value.

A still further object of my invention is to provide an electric switch characterized by the provision of relatively movable contact members, one of which is pivotally 30 mounted and provided with a reciprocatory contact portion movable into and out of engagement with the other of said contact members.

A still further object of my invention is to 35 provide a switch of the class described comprising a pair of relatively movable contact members, one of which is provided with a reciprocatory contact portion cooperating with the other of said contact members, and 40 common actuating means for the reciprocatory contact portion and the contact member carrying the same, the movement of said contact portion being independent of that of the supporting contact member within pre-determined limits.

Other objects and applications of my invention, as well as details of construction and operation, whereby my invention may be practiced, will be apparent from the following description and claims, when taken in connection with the accompanying drawings, wherein

Figs. 1 and 2 are side elevational and top plan views, respectively, of a high-tension

switch constructed in accordance with my 55 invention;

Fig. 3 is a view similar to Fig. 2, but showing a modification; and

Fig. 4 is a fragmentary, side elevational view of the structure of Fig. 3. 60

In the illustrated form of embodiment of my invention shown in Figs. 1 and 2, a longitudinally extending beam 1, which may be supported on a transmission line tower (not shown), provides a rigid mounting for spaced 65 parallel stacks of insulators 2 and 3. The upper end of the vertical insulator-stack 2 is provided with a stationary contact element 4 having a bifurcated end portion 5 forming spring contact blades 6 and 7. The 70 bifurcated end portion 5 is adapted to receive a reciprocatory or relatively movable contact portion 8 of a switch blade 9, a main body portion 10 of which is mounted to swing in a vertical plane on a pivot pin 11 carried by 75 a bracket 12, the latter being supported on an upper end of the vertical or upright insulator-stack 3, all as will appear more fully hereinafter.

The main body portion 10 of the switch 80 blade 9 preferably comprises members 13 and 14, corresponding ends of which are secured in perforated lugs 15 and 16 which are mounted in spaced relation on the pivot pin 11. The bracket 12 is provided with spaced 85 lugs 17 and 18 also perforated to receive the pivot pin 11 and they are positioned intermediate the perforated portions of the lugs 15 and 16. The lugs 15 and 16 may be further secured in position by means of nuts 19 90 and 21. A terminal lug 22 for switch blade 10 is mounted on the bracket 12 and it is connected by means of conductors 23 with the lugs 15 and 16.

The opposite ends of the sections 13 and 14 95 of the main body portion 10 are rigidly secured together by means of a connecting member 24 which is further provided with a longitudinally extending perforation 25 adapted to receive the reciprocatory contact portion 8 of the switch blade 9. The outer 100 end of the reciprocatory contact 8 normally engages the spring contact blades 6 and 7 of the stationary contact element 4, when the switch is in the closed position shown in Fig. 1, and it may be guided into this position by means of a shoulder 26 formed on the switch 105 element 4, as further explained hereinafter.

The spring contact blades 6 and 7 of the bifurcated end portion 5 may be protected from ice and snow by means of a cover 27, of which one end is open to receive the reciprocatory contact 8. The cover 27 may be supported on a shoulder 28 formed on the stationary contact element 4. The shoulder 28 may also serve as a support for a terminal lug 29.

In order to actuate the above-noted movable switch parts, I provide a third stack of insulators 30, which may be mounted intermediate the insulator-stacks 2 and 3 for rotation about a vertical axis parallel to the plane of movement of said movable switch parts. The lower end of the insulator-stack 30 is mounted on an antifriction thrust bearing 31 carried by the supporting structure 1 and it is provided with a toothed end portion 32 adapted to mesh with a bevel-gear wheel 33 mounted on a shaft 34 driven by a motor (not shown). The upper end of the insulator-stack 30 is provided with a vertically extending shaft portion 35 journaled in an antifriction bearing 36 supported by arms 37 and 38 constituting integral extensions of the bracket 12. One advantage of the foregoing construction resides in the fact that the blade-carrying insulator-stack 3 and the rotatable insulator-stack 30 are connected at their adjacent ends, so that stresses incident to the actuation of the switch blade 9 are confined to said insulator-stacks and their immediate connections, all as will presently appear.

Attention is directed to the fact that an important feature of my invention is the provision of means for so operatively associating the actuating insulator-stack 30 and the movable switch parts that the torsional strain in the insulator-stack 30 at no time reaches a dangerous value with the ordinary accumulations of ice or snow present. To this end, the insulator-stack 30 is operatively associated with the body portion 10 and the reciprocatory portion 8 of the switch blade 9 by mechanism 39, which is so designed that said movable switch parts will move only a small amount in response to a relatively large movement of the rotatable insulator-stack 30. That is to say, said mechanism 39 is so designed that the mechanical advantage of the actuating insulator-stack 30 is very large. For purposes of illustration, I have shown the mechanism 39 as a special form of screw gearing, though of course my invention is not to be limited thereby.

This so-called screw-jack connection 39 between the insulator-stack 30 and the movable switch parts involves the use of a worm 41, which is mounted on the upper end of the shaft 35, and a worm-wheel 42, which has been shown as a quadrant pivotally mounted on the pivot pin 11 intermediate the bracket lugs 17 and 18. The quadrant 42 is provided with a vertically extending arm 43, the end of which

is operatively associated by means of a link 44 with the inner end of the reciprocatory contact 8, whereby the latter may be moved in accordance with the direction of rotation of the insulator-stack 30. The quadrant 42 including pairs of oppositely extending arms or abutments 45 and 46 which are positioned on opposite sides of the body portion 10 of the movable switch blade 9 and which are successively movable into abutting relation with the upper and lower sides thereof, whereby the reciprocatory contact portion 8 may be actuated a predetermined amount prior to the actuation of the switch blade 9 as a whole. The point of engagement of the quadrant 42 with the switch blade 9 is spaced from the mounting pin 11 sufficient to provide the desired leverage. As shown in the drawing the worm 41 has a relatively flat pitch, so that the worm 41 and wheel 39 may be non-reversing under the action of the switch blade 9. This non-reversing or non-overhauling characteristic is particularly important since the switch blade 9 is locked in any desired elevated position regardless of whether or not power is applied to the actuating insulator-stack 30. Should the insulator-stack 30 break for any reason while the switch blade 9 is in either its elevated or lowered positions, the operating insulator-stack 30 provides an intermediate fulcrum, the parts of the switch blade 9 on one side of the stack 30 counterbalancing those on the other side.

When the switch is in the closed position shown in Fig. 1, the reciprocatory contact portion 8 thereof is in engagement with the contact blades 6 and 7 of the stationary contact element 4, and the arms 45 and 46 are equally spaced on opposite sides of the members 13 and 14 of the main body portion 10. If the insulator-stack 30 is now turned, the quadrant 42 and the lever arm 43 are moved, causing the reciprocatory contact 8 to be actuated out of engagement with the stationary contact element 4. At this point, the lower arms 45 are in engagement with the main body portion 10 of the switch blade 9, so that the continued movement of the quadrant 42 causes the main body portion 10 to be pushed in a vertical plane about the pin 11 as a pivot, carrying with it the reciprocatory contact portion 8. This movement may be continued until the switch blade 9 has been actuated a desired distance from the stationary contact element 4, one such position being shown by dot-and-dash lines in Fig. 1.

When the direction of rotation of the insulator-stack 30 is reversed, the movable switch blade 9 by reason of its weight will follow the downwardly moving arms 45, but should there be a tendency for the switch blade 9 to stick in its raised position, then the arms 46 will be actuated into engagement with the upper side of the switch blade 9 forcibly actuating the same downwardly. Ex-

perience has shown, however, that once the switch blade 9 has started moving downwardly, the weight thereof is sufficient to cause the same to drop down onto the supporting 5 arms 45. The lowering of the switch blade 9 continues until the outer end of the connecting member 24 engages the guiding shoulder 26 on the stationary contact element 4.

The continued movement of the quadrant 10 42 causes the arms 45 to be actuated out of engagement with the main body portion 10 of the switch blade 9 and the reciprocating contact portion 8 to be moved into engagement with the contact blades 6 and 7 of the 15 stationary contact element 4, whereupon the operation of the actuating insulator-stack 30 may be discontinued in the usual manner. When the switch is to be again opened, the foregoing procedure is repeated.

20 The modification shown in Fig. 4 differentiates over that of the preceding figures in the fact that the quadrant 42 is rigidly secured in engagement with the movable switch blade 9, say by a pin 47. The operation of 25 this modification is similar to that of the preceding figures with the exception that relative movement between the quadrant 42 and the movable switch blade 9 does not obtain.

30 While I have shown only two embodiments of my invention, for the purpose of describing the same and illustrating its principles of construction and of operation, it is apparent that various changes and modifications 35 may be made therein, without departing from the spirit and scope of my invention, and I desire, therefore, that only such limitations shall be imposed thereon as are indicated in the appended claims or as are demanded by the prior art.

I claim:

1. In a switch, the combination with a stationary contact member, of an elongated movable contact member having a main portion 45 and a contact portion movable longitudinally of said main portion, and worm-and-wheel means for successively actuating said contact portion and said movable contact member as a whole in timed relation.

50 2. A switch comprising relatively movable contact members, of which one member is provided with a contact portion relatively movable with respect to said last-mentioned member, and actuating means including worm-and-wheel mechanism for relatively and bodily moving said last-mentioned contact member and said contact portion.

3. In an electric switch, the combination with a stationary contact member, of a co-operating movable contact member having a main portion and a reciprocatory portion, and actuating means for said main portion and said reciprocatory portion, said actuating means including worm-and-wheel 65 mechanism.

4. In combination, a switch element, a bodily movable switch element having a main portion and a relatively movable portion adapted to co-act with said first-mentioned switch element, and screw-jack means for actuating said contact portion independently of said main portion out of engagement with said first-mentioned switch element and thereafter moving together said main portion and said contact portion. 75

5. A disconnecting switch comprising a stationary switch element and a pivoted switch element having a reciprocally mounted contact portion adapted to co-act with said stationary switch element, and worm-and-wheel mechanism for relatively and for bodily moving said reciprocatory contact portion and said pivoted switch element. 80

6. An electric switch comprising a pair of substantially parallel insulators positioned in spaced relation, relatively movable contact members respectively mounted on said insulators, a third insulator positioned intermediate said pair of insulators and revoluble about its axis, and means extending between said revoluble insulator and at least one of said movable contact members comprising a worm-and-wheel, said wheel being adapted to push said last-mentioned contact member between desired positions. 95

7. In an electric switch, the combination with a pair of stationary insulator stacks disposed in spaced relation and stationary and movable contact elements respectively carried thereby, said movable contact element having a relatively movable portion co-acting with said stationary contact element, of an actuating insulator stack rotatable about its axis, and connecting means extending between said rotatable insulator stack and said movable contact element and portion comprising worm-and-wheel mechanism. 100

8. In combination, a pair of spaced insulators rigidly secured in position, stationary and relatively movable contact elements respectively carried thereby, said movable contact element having a reciprocally mounted contact portion adapted to co-act with said stationary contact element, actuating means comprising an insulator rotatable about its vertical axis, and means including non-reversing gearing for operatively associating said actuating means with said movable contact element and said reciprocatory contact portion. 110

9. An electric switch comprising a pair of stationary insulators, a stationary switch element mounted on one insulator and a vertically swinging switch element mounted on the other of said insulators, said last-mentioned element having a reciprocally mounted portion adapted to co-act with said stationary switch element, an actuating insulator, a worm carried by said actuating insula- 125 130

tor, a worm-wheel section meshing therewith, said worm-wheel section being pivotally mounted on one of said stationary insulators, a lug carried by said worm-wheel section adapted to engage said movable switch element when said worm-wheel has moved through a predetermined angle, and an arm carried by said worm-wheel operatively associated with said reciprocatory switch portion, whereby the latter may be moved a predetermined amount as said worm-wheel moves through said predetermined angle.

10. An electric switch comprising a pair of stationary insulators, a stationary contact element carried by one of said insulators, a movable contact element comprising a main portion pivoted to the other of said insulators, a reciprocatory portion mounted on said main portion and adapted to co-act with said stationary contact element, a rotatable insulator provided with a worm, a worm-wheel section meshing therewith and carried by one of said stationary insulators, means for operatively associating said worm-wheel section and said main contact portion, said means permitting a predetermined amount of lost motion therebetween, and means operatively associating said worm-wheel section and said reciprocatory contact portion, whereby the latter may be moved a predetermined amount while the main contact portion remains stationary.

11. An electric switch comprising a pair of supporting insulators, relatively movable contact elements respectively mounted on said insulators, an actuating insulator positioned intermediate said pair of insulators, and means including screw gearing for operatively associating at least one of said relatively movable contact elements and said actuating insulator.

12. In combination, an actuating insulator stack provided with a worm, a movable switch blade, and a wheel element having a member movable by said worm into abutting relation with said blade.

13. In a switch, a pair of insulator stacks, a contact element mounted on one insulator stack, a relatively movable contact element, a bracket mounted on the other of said insulator stacks and affording said last-mentioned contact element a mounting, an actuating insulator stack positioned intermediate said first-mentioned stacks having one portion thereof journaled in a bearing afforded by said bracket, and screw gearing extending between said last-mentioned movable contact element and said actuating stack.

14. In combination, a switch blade, means for actuating said switch blade, and means including a wheel for establishing a lost-motion screw-jack connection therebetween, whereby the strain in said actuating means may be reduced to a minimum value, said

wheel and said switch blade having co-axial mountings.

15. A movable insulator carrying a worm, a movable switch blade, and a wheel in direct engagement with said blade, said worm-and-wheel being substantially non-reversible under the effect of said switch blade.

16. In combination, a switch blade, an operating member, and means for interconnecting the same, said means comprising non-reversing mechanism including a worm-and-wheel, said wheel being movable into and out of abutting relation with said switch blade depending upon the direction of movement of said operating member.

17. In a device of the class described, the combination with a switch blade, of an operating member, and means including a wheel for so interconnecting said operating member and said blade that the latter may be moved into an open position and thereafter held in said position, said wheel having a crank arm, and means affording said switch blade and said wheel and crank arm a common pivotal mounting.

18. In a device of the class described, a switch blade, a driving worm, and a driven wheel having an element movable into abutting relation with said switch blade to actuate the same.

19. In combination, a switch element having a mounting, a driving worm, and a driven wheel segment having an element movable into abutting relation with said switch element at at least one point spaced from said mounting sufficient to provide a desired leverage.

20. In combination, a switch element having a mounting, an operating member, and gear-wheel mechanism for interconnecting said operating member and said switch element, whereby the former may be substantially non-reversible under the load of said switch element, said mechanism including a gear element having a member in engagement with said switch element at at least one point spaced from said mounting sufficient to provide a desired leverage.

21. In combination, a switch element having a mounting, an operating insulator stack, and non-overhauling gear-wheel mechanism for operatively associating said insulator stack and said switch element, said mechanism including a gear-wheel having a mounting coaxial with the mounting of said switch element and in engagement with said element at at least one point spaced from said first-mentioned mounting sufficient to provide a desired leverage.

22. In combination, a switch blade, a driving worm, a driven wheel provided with a crank arm, means for connecting said arm and said switch blade, and means affording said wheel and said switch blade axially aligned mountings.

23. In combination, spaced relatively movable contact members, insulator stacks for respectively affording mountings for said contact members, an operating stack positioned intermediate said supporting stacks, and gear-wheel mechanism for operatively associating one of said contact members and said operating stack, said mechanism including a gear-wheel in engagement with said last-mentioned contact member at at least one point spaced from one of said mountings sufficient to provide a desired leverage.
24. A pair of relatively movable contact members, insulators respectively affording said contact members supporting mountings, an operating insulator, and non-overhauling mechanism responsive to said operating insulator adapted to move one of said contact members, one element of said mechanism having a mounting coaxial with the mounting of said last-mentioned contact member and in engagement therewith at a point spaced from said last-mentioned mounting sufficient to afford a desired leverage, said operating insulator being positioned to constitute an intermediate pivot for said last-mentioned movable contact member should its supporting insulator be rendered ineffective.
25. In combination, relatively movable contact members, of which one is provided with a relatively movable portion, and actuating means for at least one of said contact members including gearing, said means permitting a predetermined lost-motion between itself and said last-mentioned contact member.
26. A switch comprising relatively movable contact members, of which one is provided with a relatively movable portion, and screw-jack means for actuating at least one of said contact members, said means having a lost-motion connection with said last-mentioned member permitting a predetermined relative movement between the latter member and said contact portion.
27. A switch comprising a pair of insulators, contact elements respectively supported on said insulators, one of said contact elements being movable, one of said elements also having a relatively movable contact portion, an actuating insulator, and means including worm-and-wheel mechanism for operatively associating said actuating insulator and at least one of said contact elements.
28. A switch comprising a pair of insula-
- tors, contact elements respectively mounted thereon, at least one of said contact elements being movable and provided with a relatively movable contact portion, an actuating insulator rotatable about its axis, and means including worm-and-wheel mechanism for operatively associating said actuating insulator and said movable contact element and relatively movable contact portion, said means permitting a predetermined lost-motion.
29. An electric switch comprising a pair of upright insulator stacks disposed in spaced relation, relatively movable contact members respectively mounted on said insulator stacks, a third insulator stack rotatable about its axis, and means extending between said rotatable insulator stack and at least one of said contact members comprising a worm-and-wheel, whereby a maximum force may be exerted on said last-mentioned contact member with a minimum strain in said third rotatable insulator stack.
30. A switch comprising a pair of insulators disposed in spaced relation, one of said insulators being rotatable about its axis and provided with a worm, the other of said insulators being adapted to provide a mounting for a movable switch element and a wheel, said wheel extending between said insulators so as to mesh with said worm.
31. A switch comprising a plurality of insulators, a movable switch element, and means for actuating said switch element comprising a worm and wheel, said worm being mounted on one insulator and said wheel being mounted on another insulator.
32. A switch comprising a pair of insulators, relatively movable contact elements respectively carried by said insulators, an actuating insulator, and means for operatively associating at least one of said relatively movable contact elements and said actuating insulator, said means including screw gearing.
33. A switch comprising a plurality of insulators, a movable switch element, and means for actuating said switch element comprising a worm and wheel, said worm being mounted on one insulator and said wheel being mounted on another insulator, said wheel being adapted to exert a desired leverage on said movable switch element, so that the strains in the insulator on which said worm is mounted may be reduced to a minimum.

WILLIAM R. HUTTINGER.
